UNITED STATES PATENT OFFICE.

HERMAN FRASCH, OF LONDON, ONTARIO, CANADA.

REFINING CANADIAN AND SIMILAR PETROLEUM-OILS.

SPECIFICATION forming part of Letters Patent No. 378,246, dated February 21, 1888.

Application filed February 21, 1887. Serial No. 228,403. (No specimens.)

To all whom it may concern:

Be it known that I, HERMAN FRASCH, a citizen of the United States, residing at London, in the Province of Ontario, Canada, have 5 invented certain new and useful Improvements in Refining Canadian and Similar Petroleum-Oils, of which the following specification is a full, clear, and exact description.

This invention relates to the treatment of 10 Canadian and similar petroleum—such, for example, as that found at Lima, in Ohio. This oil requires a different treatment from the ordinary American oil, because of its penetrating disagreeable odor when burned and of its 15 giving off products which smoke and cloud the lamp-chimneys. These bad qualities are attributed mainly to the existence in the oil of sulphur, which is converted on burning into sulphuric acid, that collects on the chimney 20 and causes nitrogen products—such as ammonia, for example—and the unconsumed portions of carbon and also particles floating in the air to adhere thereto. The sulphur is present in these oils in considerable proportions—say upward of one-half of one per 25 centum, ($\frac{1}{2}$ of 1%), mostly in chemical combination—and some, at least, of the sulphur-containing compounds are essentially different from the sulphur compounds which occur in 30 other oils—as, for example, in coal or shale oils—and are retained with great tenacity. The large proportion of sulphur will generally 35 distinguish these from other petroleum-oils; but a further distinction may be found in the nature of the sulphur-containing bodies—namely, that they or some of them give the 40 oils the property of dissolving oxide of lead, (litharge,) or may be converted by ordinary distillation, for example, into bodies which 45 impart that property to the oils. To deprive these oils of the sulphur and other injurious compounds, and thus make them burn as well as American oil, (that is, oil such as generally obtained from the Pennsylvania oil districts,) is the object of the present invention.

Heretofore it has been customary in Canadian refineries (and the same treatment has been employed in parts of the United States) to take the burning oil distillate which has 50 been subjected to the action of sulphuric acid and washed with water and to treat the same with a solution of plumbate of soda in order

to deodorize it, and then to add sulphur in powder in order to restore the color which the plumbate solution has turned to a yellow 55 or brown, and cause the quick precipitation of the lead, leaving the oil above it white and clear. The solution of soda settles to the bottom. Before adding the sulphur it is customary to remove a small portion of the oil under 60 treatment, and after sulphuring down this portion (that is, after throwing down the lead sulphide by addition of sulphur) to test it with fresh plumbate solution. If it remains unchanged, it is considered that sufficient of the 65 plumbate solution has been added to the main body of oil, and the workman then adds the sulphur to it; but if the small portion tested is changed more of the plumbate solution is added to the main body until a removed portion 70 will stand the test. The objections to this old deodorizing process are twofold—first, an excess of sulphur is liable to be added in the second stage, which is injurious to the oil, and, secondly, the treatment is not thorough, for 75 if the oil be distilled after it has been so treated as to stand the test, with or without sulphuring down, the distillate will not stand the test, but will be discolored by the addition of the plumbate-of-soda solution. Only the more- 80 easily acted upon portion of the sulphur compounds is therefore removed by this process.

I have discovered that by distilling the oil with suitable metallic oxides or suitable compounds of such oxides dissolved in or mixed 85 with the oil not only may the rapid separation be effected of those sulphur compounds which the old plumbate of soda and sulphuring-down process would remove, but if the supply of oxide or its compound be kept up during distillation, by the use of a sufficiently large portion of the oxide or compound at the start or by additions during the operation, the removal may be effected of all or of practically 90 all the sulphur compounds, even those which would remain in the oil after the old treatment, so that this distillate may be redistilled and still stand the plumbate-of-soda test. In other words, there is generally present in the oil a certain amount of sulphur in such chemical combination that it will be bound by the 95 lead of the plumbate solution and an additional portion which the latter, although in excess, will not act upon; but the oxide or its 100

compound in my improved process may be effectively employed in excess of the quantity requisite to bind the first-named portion of sulphur, and such excess may be sufficient to bind the whole of the sulphur present.

When the oxide or compound is used in the still in solid state, it is preferably in as fine a powder as practicable in order to bring about a more ready diffusion, and it is also advantageous to use in admixture therewith a substance specifically lighter, such as plaster; but it is not necessary to employ it. The admixture of the oxide or compound with the oil is or may be secured by suitable agitating means, such as steam-jets or a mechanical stirrer or stirrers. The introduction of the purifying agents during the distillation may be effected in large or small quantities by injecting the same in solution or in solid form into the vapor-space of the still or into the oil direct, or other suitable means of introducing it could be employed.

Suitable oxides are those of metals which give up their oxygen with comparative readiness, so that they may serve as oxidizing agents toward the sulphur compounds, and are especially those of metals which form sulphides convertible into oxides by roasting and oxidation. The oxides of lead, bismuth, cadmium, mercury, copper, and silver are well suited to the purpose, also the binoxide of manganese, except for the difficulty of revivification; but the ferric, stannic, and antimonic oxides, cuprous oxide, and the oxides of nickel, cobalt, and zinc are useful, although requiring longer maceration and slower distillation. They are specially useful in connection with those first mentioned, including manganese binoxide. Manganese oxide and the oxides of palladium and rhodium may be used.

Suitable compounds of the oxides are those which are readily broken up, such as the carbonates, for example, of the oxides just named. By distilling the oil with one or more of these oxides or their carbonates the sulphur compounds are broken up and sulphur is precipitated as a sulphide or sulphides. As distillation and precipitation proceed, fresh quantities of the oxides can be taken up by the oil and should be supplied from the original charge or from material introduced during the operation, so as to keep the oil always saturated therewith. The vapors given off from the oil or solution are or may be condensed in any ordinary or suitable way, and if the distillation be properly conducted the condensed liquid or distillate will stand the test with plumbate of soda throughout the operation.

I have also discovered that the distillates from the preceding operation, although standing the plumbate-of-soda test, yet contain compounds products of that operation which impair somewhat the quality of the oil, and that these ingredients are removed by treatment with sulphuric acid, washing with water, and neutralizing as customary in refining American petroleum; but it is not necessary to treat

the distillates with sulphuric acid in order to secure a useful result. Without such treatment they are far superior to the oils heretofore produced from Canadian and similar petroleum.

I have further discovered that a sulphide precipitate or deposit—such as accumulates in the still as the result of the distillation with oxides, as before described, revivified by roasting and oxidation—can successfully be employed in treating Canadian and similar oils for the removal of the sulphur compounds contained therein. If any heavy oil remains in the still, it may be separated from the solid portion of the residuum by settling and decantation, or by straining, or partly by both; or the liquid portion (all or partly) may be distilled off, in which last-mentioned case any dissolved oxide is added to the deposit, whereas in other cases it is drawn off with the liquid and can be added in solution to a new charge. Some of the liquid may adhere to the deposit; but its presence is not objectionable, but rather advantageous, as assisting in maintaining the temperature of the furnace. The roasting and oxidation can be performed in a furnace such as employed in the most analogous metallurgical operations.

Crude petroleum may be treated in the manner described; but for local and industrial reasons it is preferred to treat the burning oil obtained by distilling the crude oil in the ordinary way. One reason for the preference is that the residuum is large in treating crude oil and the distillation of the said residuum is necessary, in order to recover the metallic oxide (or its compound) dissolved therein.

In practically applying the treatment to the burning oil distillate about ten to fifteen per centum (10% to 15%) of heavy oil is added thereto, with the oxide or its compound, and after the burning oil has been distilled off the heavy oil holding the metallic oxide or its compound in solution is added, together with the proper amount of additional oxide, to the next charge to be distilled, and so on. This procedure is of course not essential to the invention.

In order the better to enable those skilled in the art to practice the invention, the following detailed description is given, it being understood that the invention is not restricted to the numbers stated, nor to other details, but that these are given only by way of example.

An ordinary three-hundred-barrel still is supplied with three hundred barrels (300 bbls.) of oil, composed of, say, fifteen per centum (15%) of heavy oil of from thirty-six to thirty-nine degrees Baumé (36° to 39° B.,) and the remainder of burning oil distillate boiling at two hundred and twelve degrees Fahrenheit (212° F.) or over. To this oil is added a mixture of sixteen hundred pounds (1,600 lbs.) of plumbic oxide, three thousand pounds (3,000 lbs.) of cupric oxide, and three thousand pounds (3,000 lbs.) of plaster-of-paris, all finely ground, mixed, and bolted. Plumbic and cu-

pric oxides are used because they act very energetically and reduce quickly and without loss. One of them could be used alone, or one or both could be replaced by or used in connection with another agent or agents, as hereinbefore indicated, and the plaster might be omitted. As soon as the still is charged it is fired, and when the temperature reaches two hundred and twelve degree Fahrenheit (212° F.) or over, according to the boiling-point of the oil, steam is injected at the bottom, so as to agitate and mix together the contents of the still; or if a mechanical agitator is employed, it is set in operation as soon as the firing is commenced. The agitation is continued during the whole run. When the burning oil has been distilled off and only the heavy oil remains, the still is shut down, and when cool all the liquid portion of the residuum is drawn off and the remainder or solid portion is shoveled into a strainer or bed having a canvas-lined false bottom, under which a vacuum is maintained, say, by a steam-jet, in order to expedite draining. The liquid filtered or strained off, and also that drawn from the still, is introduced into the still with another charge of the burning oil distillate sufficient in quantity to make up three hundred barrels, (300 bbls.,) the quantities of oxide and plaster before mentioned are then added, and the burning oil is distilled off, as before. The same round of operation is then repeated.

The powder remaining on the strainer or canvas, when freed as much as practicable from oil, is thrown into the front part of a roasting-furnace a portion at a time and ignited. The oil adhering, in connection with the sulphur and metal, furnishes all the heat necessary for roasting. The air will supply the oxygen, so as to effect the revivification at one operation. As each fresh portion is added the portions previously introduced are pushed back until the whole charge has been trans-

ferred to the furnace. The mass becomes red hot and is thoroughly roasted. The fine division of the powder and its composition insure a perfect and quick roasting. It is stirred until below red heat, and is then discharged from the furnace, reground, and bolted, and is ready to be added to a fresh charge of oil to be distilled.

It is evident that parts of the invention may be used separately, as well as that modifications can be made in details without departing from the spirit of the same.

The proportion of oxides should correspond to the sulphur in the oil, which varies in oils even from the same locality. Those given are ample to treat oil containing one per centum (1%) of sulphur. If the portion of sulphur is considerably higher, they should be increased.

I claim as my invention or discovery—

1. The process of purifying Canadian and similar petroleum-oils which contain sulphur compounds whose presence gives to said oil the property of dissolving lead oxide by distilling the same with the oxidizing oxides, especially the roasted and oxidated residues of previous operations, mixed with or dissolved in the oil under treatment, substantially as described.

2. The process of purifying Canadian and similar petroleum-oils which contain sulphur compounds whose presence gives the said oil the property of dissolving lead oxide by distilling the same with the oxidizing oxides, especially the roasted and oxidated residues of previous operations, mixed with or dissolved in the oil under treatment, and washing the distillate from such operation with sulphuric acid, substantially as described.

In testimony whereof I have signed this specification in the presence of two witnesses.

HERMAN FRASCH.
